UNITED STATES PATENT OFFICE.

EDME ETIENNE JOSEPH BONNEAU, OF PARIS, FRANCE.

GYROSCOPIC TOP.

Application filed January 15, 1919. Serial No. 271,280.

To all whom it may concern:

Be it known that I, EDME ETIENNE JOSEPH BONNEAU, of 15 Rue Beudant, Paris, France, have invented Improvements in or Relating 5 to Gyroscopic Tops, of which the following is a clear, full, and exact description.

This invention has reference to gyroscopic tops with direct polar correction without precession and the said invention relates to 10 an improvement made in the construction of gyroscopic tops, employed particularly to furnish a stable indication of the vertical or of the plane of the horizon.

The proper characteristics of this improvement proceed from the following considerations:

The various present gyroscopes of the top kind, that is to say supported by a single pivot, have for their type the gyroscopic 20 sextant of Fleuriaux who has defined the conditions of construction and use thereof to be viz.

1. Placing the centre of gravity a little below the point of the pivot.
- 25 2. Employing as fine a pivot point as the conditions of mechanical resistance permit.
3. Only utilizing the top at extremely high speeds (4,000 to 5,000 revolutions).

A gyroscope of this kind when a very low 30 speed of rotation is imparted thereto preserves an easy pendular stability, but as soon as its rotation becomes rapid its movement is solely governed by the following phenomena:

- 35 4. If its axis be supposed to be inclined to the vertical, the effect of the weight is to cause said axis to describe with a uniform speed a circular cone around the vertical (precession). At the same time the asymmetric friction of the point bearing obliquely upon its bearing develops at the point of contact a small horizontal frictional force which gives rise to a couple of gyrostatic reaction tending to correct the oblique axis 40 of the gyroscope and to bring back the speed of precession.

The result of these two actions is definitely to bring back slowly this axis into the vicinity of the vertical when it has been 45 shifted away therefrom, by a series of circular oscillations smaller and smaller and very long in vanishing, its pole describing in space a loxodromic trajectory.

Experience has shown that such apparatus 50 are of little use in practice as indicators of

the vertical by reason in particular of the following disadvantages:

1. These instruments cannot furnish instantaneous indications, the slowness of the oscillations of the axis about its position of 60 equilibrium compelling this to be defined by means of maximum elongations of the axis observed on each side of it.

2. By reason of the lowering of the centre of gravity below the point of the pivot, these 65 instruments are very sensitive to all the forces acting laterally on the top for example to horizontal accelerations, which, if they are important (as on board flying machines), completely falsify the observations. 70

3. None of these disadvantages can be remedied (by augmentation of the pendular stability or increase of the speed of rotation) without developing the other disadvantage 75 simultaneously.

It has only been possible hitherto to obtain imperfect instruments, by choosing for them empirically mean conditions.

The invention forming the subject-matter of the present invention relates to an 80 improvement in gyroscopic top for causing the axis of this top to take, under the effect of the rotation alone of the latter, without the help of any auxiliary member, a polar setting in the direction of the vertical, without conical precession and to remain in stable equilibrium in this position.

This improvement is essentially characterized in that the top has a spherical pivot the centre of which coincides with the centre 90 of gravity of this top and which rotates on a step bearing having a greater radius of curvature than the radius of the sphere of this pivot, so that the latter is in contact at one point with the said bearing. 95

By way of example, the invention is represented in the accompanying drawing in which:

Figure 1 shows in vertical section the present improved arrangement of gyroscopic 100 top applied as a level indicator.

Figure 2 is a detail view of the pivot.

As shown in this drawing, the body *a* of the top has a pivot *b* the end of which has the form of a sphere or of a portion of a 105 sphere *c*, also the whole of the body *a* and of its pivot *b* is so constituted that the centre of gravity *G* of the top is situated at the centre of this sphere or portion of a sphere *c* of the pivot.

The spherical end *c* of the pivot *b* of the top rests in a bearing *d*.

By this arrangement the top is situated in a state of inert equilibrium upon its bearing, and in consequence of this fact its working conditions differ from those of the present gyroscopic tops particularly by the following points:

1. The precession is completely suppressed by the fact of the inert equilibrium of the top upon its supports; any correction necessary for this can therefore be made directly and without oscillations.

2. The apparatus is only sensitive to horizontal accelerations and to other lateral forces, as far as these have previously determined a movement of the top parallel to itself, sufficient to move the point of contact of the pivot sphere upon the bearing. In practice these actions, if they are of feeble duration relatively to the conditions of utilization, will not disturb the position of equilibrium of the gyroscope, in contradistinction to the case in which (as in the present gyroscopic tops) they act directly upon the mass of a gyroscope suspended pendularly, that is to say the centre of gravity of which is situated below the point of the pivot.

30 Experience shows that the axis of a top constituted according to the present invention, rotating at a low speed (500 to 600 revolutions only), forms an instantaneous and stable indicator of the vertical, the correction of which in case of disturbance is direct, without precession or oscillation and the disturbances of which under the action of momentary lateral forces are particularly feeble. This result, which has not hitherto been obtained by any system of gyroscopic top, renders the present top particularly suitable for the realization of an inclination indicator for aerial or maritime navigation.

The body *a* of the top may present as shown in Figure 1 an external surface *a'* of spherical form concentric with the pivot sphere *c*.

In this case, the properties of the pivot sphere being extended to the surface of the body of the top, the latter reacts, under the action of a tangential contact effected above its equatorial plane, by a correction in a determined direction, that is a positive correction; on the contrary, if the contact is effected below this plane, by a correction in the opposite direction, that is a negative correction. By the term "equatorial plane" is meant a plane perpendicular to the axis of rotation of the top and passing through the center of gravity of the top. Consequently, when the body of the top has a spherical external surface, the axis of the top will be moved in a pre-determined direction if a contact is applied to said spherical surface at a point located above the equatorial plane;

if the contact is applied at a point below said plane the axis of the top will be moved in the reverse direction; finally, if the contact is applied at the point on the circle located within said equatorial plane, the axis of the top will not be displaced.

The equatorial plane constitutes therefore a neutral plane in which tangential forces may be exerted upon the body of the top without the equilibrium of the latter being disturbed.

The present system of gyroscopic top by reason of its special qualities is capable of receiving numerous industrial applications; this top may be utilized in particular for the constitution of horizon indicating apparatus; in this case, the apparatus will be provided with any appropriate arrangement capable of measuring relative inclinations of the axis or of the equatorial plane of the top with relation to the mounting of the instrument, such as a mirror, a luminous spot, an index, carried by the axis of the top, etc.

This system of gyroscopic top is likewise applicable, by reason of the above faculty of supporting equatorial contacts without disturbance, to the realization of an arrangement for operating a servo-motor transmitting to a distance the variations of position of the top, either to indicating apparatus distributed at different points, where it is necessary to let the measure of the inclination be known, or to automatic operating apparatus, such as diving or steering rudders, intended to ensure automatically the keeping of an airship or submarine in a determined position of equilibrium.

Fig. 5 shows diagrammatically, and by way of example, a device for following up the lateral tilts of the improved gyroscopic top. The top *a* carries in its equatorial plane two flexible brushes *m* *m'* diametrically opposed to one another; these brushes engage the smooth inner surface of a spherical housing within which is mounted the support *d* of the top. The said housing comprises four spherical segments *n*, *o*, *p*, *q* of metal, separated from one another by insulating rings *r*, *s*, situated in two perpendicular planes, one of said rings passing through the equatorial plane of the top when the latter is in its position of equilibrium, the two left hand side spherical segments *n*, *o*, are therefore diametrically opposed to the right hand side spherical segments *p*, *q*.

The lower left hand side segment *n* and the upper right hand side segment *p* are inserted in an electric circuit in which are comprised a source of electric power *t* and a small electric motor *u*. Likewise the upper left hand side segment *o* and the lower right hand side segment *q* are inserted in a circuit which is independent of that above referred to, and in which are also comprised

a source of electric power v and a small motor w .

The spherical housing within which the top rotates is carried by two trunnions and 5 is movable about an axis perpendicular to the plane of the figure and passing through the center of gravity G of the top. This spherical housing is susceptible of being moved in one or the other direction by the 10 action of the motors u, w when the circuit of one of these is closed, as explained below; to this effect each motor transmits its movement to the spherical housing with a reduced speed, as for example, through a 15 train of reducing gears in mesh with an outer toothed ring x on the spherical housing.

The operation of the device is as follows:

In the position of equilibrium, the brushes 20 $m m^1$ engage the insulating horizontal crown r ; the two electric circuits are interrupted, the motors $u w$ are not excited and therefore do not transmit any movement to the spherical housing.

25 As soon as the top tilts on its support, for example, in the direction of the arrow A , the two brushes $m m^1$ engage the two diametrically opposed spherical segments, $o q$, and thus close the circuit of the motor w ; 30 this motor, being excited, imparts to the spherical housing an angular movement about its axis of rotation in the direction of the arrow B , that is, in the opposite direction to the tilt of the top, until the insulating ring r is brought back to the plane in 35 which the brushes $m m^1$ are moved. At this moment, the circuit of motor w is cut, the latter comes to rest and the spherical housing stops.

40 If the top tilts in the opposite direction, the two brushes $m m^1$ engage the other two spherical segments p, n , and close the circuit of the motor u ; this motor on becoming

excited imparts to the spherical housing an angular movement in the direction of arrow 45 C until the insulating ring is brought back to the plane of rotation of the brushes $m m^1$. The circuit of the dynamo is then cut and the spherical housing stops.

The device just described enables the 50 spherical housing to follow up all the tilts of the top with the necessary motive power for actuating any suitable mechanism.

I claim—

1. A gyroscopic top comprising a body, a 55 spherical pivot the center of which coincides with the center of gravity of the top, and a spherical bearing for the pivot the radius of curvature of which is greater than the radius of the spherical pivot. 60

2. An indicating apparatus for measuring the tilt of a gyroscopic top, comprising a bearing and a gyroscopic top comprising a body and a pivot, said pivot having a spherical end portion resting on said bearing, the 65 center of said spherical portion coinciding with the center of gravity of said top, and the said bearing having a radius of curvature greater than that of the said spherical end portion. 70

3. An apparatus for controlling a servomotor, comprising a bearing and a gyroscopic top comprising a body and a pivot, said pivot having a spherical end portion resting on said bearing, the center of said 75 spherical portion coinciding with the center of gravity of said top, the said bearing having a radius of curvature greater than that of the said spherical end portion, and said body having an external surface concentric 80 with said spherical portion.

The foregoing specification of my improvements in or relating to gyroscopic tops, signed by me this 18th day of December, 1918.

EDME ETIENNE JOSEPH BONNEAU.
